TONE ARM

Robert S. John, Waukegan, Ill., assignor to
Pfanziehl Chemical Co., a corporation of Illinois

Application January 23, 1945, Serial No. 574,052

1 Claim. (Cl. 274—23)

This invention relates to a tone arm and particularly to a tone arm assembly in a record-playing device in which the principal function of the tone arm is to provide a movable holder to carry the translating means and needle across the record.

Among the objects of the invention is to provide a movable extension arm which will effect stable support for an apparatus capable of translating a forced vibration into a fluctuating electric current; further to provide a tone arm in which the cartridge housing the translating means is set at an angle to the arm to allow the needle to cross the record approximately on a radius and the cartridge be as nearly tangent to each record groove as possible; still further to provide a tone arm that will function with a low needle pressure and supply sufficient momentum and inertia to allow the needle to reproduce a broad range of frequencies with high fidelity; yet further, the feature of providing a novel tone arm in which the center of gravity of the cartridge and arm is near the needle point; the further feature of providing a tone arm in which the arm and cartridge are free to rotate in vertical planes and horizontal planes, but no further motion; also to provide a tone arm comprising a framework or arms made of thin wall tubing and so constructed and arranged as to prevent any wobbling of the cartridge; further the provision of a movable vibration damper that can be selectively fastened to one of the arm-members at any point where a vibration position might occur at low frequencies, and to prevent materially reduce any natural resonant frequency that might occur in the tubes of the tone arm; also to place the connecting wires inside of the tubing to shield them from any outside magnetic or electrostatic fields; to provide small surface area which reduces practically to zero any sounding board effect that might be caused by any forced vibrations that might get into the cartridge; also to provide weights for the cartridge so as to locate the center of gravity of the arm and cartridge near the needle, and yet have low needle pressure, and a light-weight arm compared to the weight of the cartridge, so that the moment of inertia of the arm and cartridge, about its horizontal pivotal support, will be as great as possible for its total weight and needle

pressure; and to provide a heavy base element on which the supported end of the arm is pivoted, to produce a high moment of inertia with a light-weight arm, that can rotate horizontally with the arm and provide an extra amount of horizontal stability for the cartridge.

Further objects, advantages and capabilities inherently possessed by my invention will later more fully become apparent.

My invention further resides in the combination, construction and arrangement of parts illustrated in the accompanying drawings, and while I have shown therein preferred embodiments I wish it understood that the same are susceptible of modification and change without departing from the spirit of my invention.

In the drawings:

Fig. 1 is a side edge elevation of a tone arm embodying my invention and showing a record table and record in dotted lines.

Fig. 2 is a top plan view of the tone arm assembly of Fig. 1.

Fig. 3 is a vertical transverse section on the line 3—3 of Fig. 2 looking in the direction of the arrows.

Fig. 4 is a view similar to that of Fig. 1 but showing a modified form of my invention.

Fig. 5 is a top plan view of the tone arm assembly shown in Fig. 4.

Fig. 6 is a vertical transverse section on the line 6—6 of Fig. 5 looking in the direction of the arrows.

Referring more in detail to the drawings my preferred form of the invention is shown in Figs. 1—3 and comprises a pair of spaced apart angularly arranged arm-elements 1 and 2 as shown in Fig. 2 and rigidly connected together at their forward ends by a connecting arm 3 and at their rear ends by a curved U-shaped member 4. The rear ends of the arm-elements are rigidly secured to the U-shaped member 4 by any suitable means to rigidly hold these parts together as a unit, the rear ends of the U-shaped members each having a hole 5 to receive a pin 6 secured one at each side in the rotor 7 so that the tone arm designated generally at T may have a vertical swinging movement about pins 6 as later more fully described.

The arm elements 1 and 2 are extended forwardly beyond the cross member 3 and bent an-

gularly a small amount as indicated at 8 and 9, these extending ends being inserted into holes in the rear end of the cartridge 10 and secured therein by set screws or the like 11 or any other suitable fastening means to hold the cartridge securely and firmly to the arm elements 1 and 2.

The translating or needle element 12 preferably consists of a small plastic moulding having a larger flag portion 13 which is held in the cartridge by any suitable number of screws 14, or other suitable fastening means, as seen in Figs. 1 and 2. The smaller extension portion or vibratory arm of this translating element holds the needle point or stylus 15. The vibratory arm is of insulating material, as polystyrene, and at least one surface has a strain-sensitive coating, as of colloidal graphite, whereby flexure of the arm varies the resistance of the coating and provides the desired electrical variations. Translating elements of this type are shown, for example, in Germeshausen Patent 2,329,526. The end of this vibratory arm must be free to follow the record groove, and the vibration of the needle point, and the bending of the needle arm, should not be transmitted to the cartridge or any other part of the whole tone arm. To accomplish this the cartridge 10, the tone arm T and the rotor 1 must provide a sufficient amount of inertia and stay within the desired low limits of needle pressure. It is desirable that the center of gravity of the cartridge and arm T should be as near the needle point and as low as possible in position and weight. To facilitate this, weight-elements 16 are provided in the cartridge near its forward end. In the particular arm and cartridge assembly here being described, the center of gravity of the combination is slightly forward of the rear end of the cartridge; and it is preferably not more than one-third of the distance from the needle to the mounting point in any construction.

The arm T and cartridge must be free to rotate in vertical planes about an axis passing through the axis of the fulcrum pins 6 and through the center of rotation of the rotor 1, which rotor rotates in a horizontal plane about its vertical axis. This vertical and horizontal movement of the arm T must be accomplished freely without any other motion. The rotor 1 is relatively heavy and has comparatively large mass distributed more or less similarly to a fly wheel, in order to provide the greatest amount of inertia for the weight actually used. For convenience the fulcrum points between the rear ends of the arm-elements 1 and 2 and the rotor 1 are indicated at A and B which points are preferably from two to three inches apart. This assembly of rotor 1, arm T and cartridge 10 provides an amount of inertia in the plane indicated by the points AB15, which holds the flag 13 of the needle in sufficient equilibrium while the needle vibrates. The construction of the rotor and the supporting parts later described should be such that the plane AB15 is either parallel to or at a small angle to the surface of the record 17 for this inertia to be most effective.

The support for the tone arm comprises the rotor 1 above referred to, the ball-type thrust bearing 18, the stator 19 and the damper 20 having a central opening 21. The stator has a central opening 22 screw threaded to receive complementary threads on the lower end of the tubular pivot pin 23 which is rigidly mounted in the stator to project upwardly therefrom through complementary central openings in the thrust bearing and the rotor, the rotor being rotatably

mounted upon tube 23 but without any looseness that might allow vibration in the rotor. The thrust bearing 18 is provided with an annularly arranged series of openings 24 receiving the anti-friction balls 25. The damper element 20 is of any suitable material to absorb any vibration that might be set up in the tone arm as a whole and to prevent any vibration being transferred from the support to the tone arm.

Longitudinally movable along either one or both of the arm-elements 1 and 2 is a vibration damper 26 which is a mass of any suitable material that can be selectively fastened to the arm-element at any point where a vibration position might occur at low frequencies, and the function of which is to interfere with any natural resonant frequency that might occur in the arm-elements and to reduce or prevent such vibrations from occurring. The arm-elements 1 and 2 are purposely made of thin-walled, small diameter, metal tubing which is grounded. The wires to the needle are placed inside of these tubes which shield them from any outside magnetic or electrostatic fields. The small surface area reduces practically to zero any sounding board effect that might be caused by any forced vibration that might get into arm T from the cartridge. The surface of the arm T, the cartridge 10 and the rotor 1 may be covered with some soft material, as a sprayed plastic coating, that will interfere with the transmission of any vibration to the air.

As will be understood the rotatable record head 17 will be driven by any suitable means within a cabinet or other suitable housing, the surface of which is indicated at 27, the support 1, 18, 19 and 20 also resting upon surface 27 at a point adjacent the edge of the rotating record holding table 17, the record being indicated in dotted lines at 28.

The form of my invention shown in Figs. 4-6 is in general the same as that shown in Figs. 1-3 except for detailed structural differences. The support for the tone arm consists of the rotor 31, stator 38, and soft vibration damping base 39, the rotor 31 being rotatably mounted on the stator 38 by means of a pin 40 threaded into the stator and having at its upper end a head 41 between which head and the bottom surface 42 of the depression 43 is mounted a spring 44 to yieldably hold the rotor against the stator, the rotor being rotatable about pin 40 with a close rotatable fit in order to prevent any vibration between these parts. Formed on the lower face 55 of the rotor is an annular flange 45 provided with a flat bottom face to have rotatably sliding movement upon the upper face 46 of the stator so as to decrease the friction between these parts and enable an easy but vibrationless rotation therebetween. This flange 45 should be of substantial diameter for stability, but not so large as the rotor 31, to minimize frictional resistance.

The tone arm indicated generally at T' in Fig. 5, comprises the arm-elements 47 and 48 which may be of any desired small cross section, these arms being preferably made of very thin metal tubing through which the wires from the needle extend. The rear end of the tone arm is pivotally mounted to the rotor by the fulcrum pins 49, the axis of which when extended intersects the axis of rotation of the rotor. The holes in the rear ends of arm elements 47, 48, through which the fulcrum pins extend, are of a close rotating fit so as to prevent rotation between these parts, the fulcrum pins 49 being threaded

into the rotor and screwed inwardly so as to permit free rotation but prevent any looseness or vibration. The cartridge is rigidly attached to the front ends of the arm-elements 47, 48, in the position shown in Fig. 5, this form of cartridge also having weight elements 50 in the forward end similar to the elements 16 in Fig. 2. The arm-elements 47, 48 are connected together at their respective ends by cross braces 51 and 52 which are held rigidly but longitudinally adjustably to these arm-elements by tightening the screws 53 and 54. Vibrational damping material will be positioned around the transverse cross brace 52 to function in a manner similar to that described above in connection with the vibration damper 26. Cross braces 51 and 52 also contain wood cross supports *e* and *f* (preferably soft wood with the grain longitudinally of the arm) which serves well as vibration dampeners and can be shifted to find an anti-nodal point. Cross braces 51 and 52, as will be understood, also give added rigidity to the tone arm *T'* as a whole. Damping material will also be positioned around the fulcrum pins 49 to further prevent vibration.

The forms of my invention described above give very desirable resilience and flexibility to the tone arm. It is important to note that the small surface area of the arm-elements of my novel tone arm reduces the effect of forced vibration, and that the damping reduces vibration from the cartridge to the arm and allows a slight flexibility which means better tracking. Also the center of gravity of the arm and cartridge combination is kept as near the needle point as possible, and my construction as described is such that it tends to have as high a moment of inertia about the pivot as is possible with its weight which is kept low by light weight construction and which in effect causes the motion of the arm and cartridge combination to simulate that of a simple pendulum.

The tone arm and cartridge of the present invention is such that the needle will track better and follow record warping or other irregularities better and with less needle pressure than any tone arms heretofore known. In the present construction I have made possible a very light needle pressure, for example between $\frac{1}{4}$ and one ounce, and preferably in the neighborhood of from $\frac{1}{2}$ to $\frac{3}{4}$ ounce, in connection with which it is important to note, as stated above, that the center of gravity is near the needle and that counterbalancing has been entirely eliminated. This device will operate efficiently at very low needle pressures. I have provided a very solid cartridge that can clamp the needle rigidly for the best results and vibration of the needle is permitted without creating undesirable vibrations in the other parts, it being noted in Figs. 1 and 2 that sufficient space is provided for around the needle portion 12, while at the same time firmly clamping the flag 13 in the cartridge and firmly connecting the cartridge to the front end of the arm-elements.

The cartridge is formed with thin construction in order to reduce its weight and still maintain its strength, it being noted that the height of the cartridge has been kept low. The balance point of the arm is quite close to the rear end of the cartridge, and this sets up a high moment of inertia considering its total weight, to resist any rotational disturbances in a horizontal plane which is the direction from which outside disturbances would come. This inertia effect must respond simultaneously with the disturbances

and will do so if the moment of inertia is as high as possible. If desired, the cartridge may be supported from the tubing of the tone arm by means of some damping material to further eliminate a transfer of vibration.

The small surface area of the tubular arm-elements reduces vibration transmitted to the air and prevents the tone arm from having action like a sounding board. The entire tone arm has a flexibility that very materially increases the life of the records. The cartridge should be comparatively flat and not too heavy in order to help minimize a twisting type of vibration that might occur especially in the cartridge in a vertical plane at right angles to the line passing through the point of the needle and the center of rotation of the rotor 7. The extra width between the points AB at the rear end of the tone arm helps reduce the objectionable vibration just referred to. The tone arm tubing serves as a shield for the wires which will run through it as stated above and the use of small tubing helps cause the bulk of the weight to be in the cartridge. Needle pressures between $\frac{1}{3}$ and one ounce are preferable, the lower values being used when sufficient tracking on the record is obtained.

In order to have the greatest possible vibration response in the needle and the least amount in the cartridge and tone arm, the metal needle tip in its plastic mould is made as light as possible and the tone arm relatively heavy. In tone arms prior to the present invention this latter weight is supplied by a heavy tone arm having a considerable amount of distributed weight, and in some tone arms the arm extends back beyond the pivotal point so as to carry a counterweight which is ample to control the needle pressure, while in some instances the arm extends back beyond the pivoted point so that a variable spring can be attached to control the needle pressure. The effect of such prior tone arm is to make the natural motions of the entire arm about a vertical axis in the base and support similar to that of the compound pendulum and thus slow and sluggish. Such compound pendulum effect also slows any tone arm motions around the horizontal axis in the support. These tone arm motions need to take place to allow the needle to track on warped or eccentric records and to move it as it follows the groove. The tone arm of my present invention has no compound pendulum effect but moves quickly and efficiently similar to the motions of a short simple pendulum and this allows it to trace any record irregularity in a much surer and positive manner.

In order to have the greatest possible vibration in the needle and the least in the cartridge and tone arm the moment of inertia of the assembly should be as great as possible consistent with its total weight, needle pressure and necessary design limitation. This relatively large moment of inertia is obtained by keeping the weight of the tone arm low and the weight of the cartridge as high as a limited needle pressure will permit. Also the center of percussion should be in the front end of the moulding that holds the metal needle. The cartridge should be kept reasonably small and as compact as possible.

Having thus described my invention, I claim:

A tone arm comprising a light-weight rigid arm having small surface area, said rigid arm comprising two spaced tubes of small diameter rigidly held for movement as a unit, a cartridge rigidly carried near one end of said arm, said cartridge carrying weights on the outer end there-

of to locate the center of gravity of the arm and cartridge nearer the cartridge than the other end of the arm, a support of relatively large mass compared to the mass of the rigid arm comprising a rotor and a stator, the rotor being rotatable on the stator in a horizontal plane, and means for mounting the other end of said tubes on opposite sides of said rotor for rotation therewith in the same direction and for pivotal movement in vertical planes, the points of pivotal mounting on opposite sides of said rotor being spaced substantially farther apart than the width of said cartridge.

ROBERT S. JOHN.
